UNITED STATES PATENT OFFICE.

PHILIPPE DE CLAMECY, OF BOSTON, MASSACHUSETTS, ASSIGNOR TO CORONA TYPE-WRITER COMPANY, INC., OF GROTON, NEW YORK, A CORPORATION OF NEW YORK.

TYPE-WRITING MACHINE.

1,315,013.

Specification of Letters Patent.

Patented Sept. 2, 1919.

Application filed January 21, 1918. Serial No. 212,967.

To all whom it may concern:

Be it known that I, PHILIPPE DE CLAMECY, a citizen of the United States, and resident of the city of Boston, county of Suffolk, and 5 State of Massachusetts, have invented certain new and useful Improvements in Type-Writing Machines, of which the following is a specification.

The main object of the invention is to provide 10 a small, light-weight typewriting machine containing the usual groups of mechanisms found in the accepted standard typewriting machine, and to simplify the construction of the machine and materially reduce 15 the number of parts in order to reduce the cost of manufacture and to produce a small portable machine.

In the drawings, Figure 1 is a vertical sectional view taken fore and rear of the machine, the platen carriage and the platen being shown in end elevation;

Fig. 2 a detail transverse sectional view of the machine showing the universal bar and the means for operating said bar through 25 the type bars;

Fig. 3 a detail view of one end of one type bar;

Fig. 4 a horizontal sectional view taken approximately on the line IV—IV of Fig. 1, 30 parts of the mechanism being omitted for the sake of clearness in illustration;

Fig. 5 a plan view of the machine;

Fig. 6 a vertical sectional view of the machine taken fore and rear of the machine, 35 showing the platen shift means;

Fig. 7 a detail horizontal view of a part of the machine showing the ribbon vibrating means; and

Fig. 8 a detail side elevation of a portion 40 of the ribbon vibrating means.

Referring to the various parts by numerals, 1 designates the main frame of the machine which is preferably formed of some light rigid material such as aluminum, said 45 frame being formed with a keyboard part 2, the ribbon-reel supporting parts 3, the type bar receiving portion 4 which lies between the ribbon-reel supporting parts, and the rear part 5 which supports the carriage bed. The usual pivot wire 6 for the type bars extends transversely of the type bar receiving portion of the main frame at the rear end thereof, and on said pivot wire the type bars 7 are mounted. Said bars nor-

mally extend forwardly from the pivot and 55 are provided with type heads 8 which rest on the type support 4^a of the main frame, suitable cushioning means being provided to receive the type when they return to their normal at-rest position. Mounted on the 60 keyboard frame part 2 are a series of upwardly extending guide tubes 9, one tube being provided for each of the type keys and the shift keys, and one for each end of the space bar. The keyboard is preferably 65 a standard or universal keyboard, but, of course, the keys may be arranged in any desired manner, one key being provided for each type bar, in the usual manner. Mounted to reciprocate vertically in each tube 9 70 is a finger key 10 having a stem 11 which fits closely in the tube. Connected to the lower end of each key tube 9 is a tubular guide 12 which is curved downwardly and forwardly at its lower end and opens into 75 an enlarged cup-shaped rigid guide 13 which inclines upwardly and rearwardly and is open at its rear end, as clearly shown in Fig. 1. Connected to the stem of the finger key is a thin, flexible operating rod 14 which 80 fits nicely in the guide tube 12, its rear end extending into the guide cup 13. This operating rod is preferably of material like piano wire, of small diameter, and fits nicely in the tube 12 so as to be guided therein and 85 prevented from buckling or twisting. Connected to the end of the operating rod within the guide cup 13 is a type bar link 15, said link being formed with an enlarged head 16 which fits normally against the forward 90 closed end of the guide cup. The link 15 is connected at its upper rear end to the type bar adjacent the pivot thereof and in such position that when the link is forced rearwardly by a downward pressure of the finger 95 key the type bar will be thrown upwardly and rearwardly to the printing point on the platen. Mounted on a longitudinally movable slide 17 is a tension-adjusting bar 18 which extends upwardly and is apertured 100 for the passage of each of the type bar links 15, the said tension bar being arranged a suitable distance at the rear of the guide cup 13. Arranged in each guide cup and bearing on the head 16 is a spring 19, the 105 rear end of said spring bearing against the tension bar 18. Threaded through the lower end of the tension bar midway the ends

thereof is an adjusting rod 20 whose forward end projects through the front of the frame of the machine and is provided with an operating knob 21. By rotating the rod 20 the tension bar 18 may be moved forwardly or rearwardly to simultaneously vary the tension of the springs 19. By this means the touch of the keys may be made uniform and may be simply and readily, simultaneously adjusted. As shown in the drawings, the tension bar is supported and guided by one slide 17 arranged midway the ends of the bar. It will, of course, be understood that the tension bar may be guided in other ways and that more than one slide 17 may be provided if found desirable. It is manifest that the type bar action is very simple; is of few parts, and that there is only one pivotal connection between the type bar and the key-operated means. This construction eliminates lost motion, reduces the difficulty of assembling the parts of the type bar action; and the type bars are moved by a direct upward and rearward thrust transmitted from the finger keys through the operating rod 14 and the connecting link 15.

The rear ends of the type bars, beyond the pivot wire 6, are formed into upwardly and rearwardly curved cams 22. Each of the cams 22 bears on a roller 23. The rollers 23 are mounted upon a common bearing rod 24 which is carried by a universal bar 25 which extends transversely of the machine. The ends of the universal bar are provided with downwardly extending guide pins 26 which fit tubular post 27 mounted on the base of the main frame, said bar being maintained yieldingly in its upper normal position by springs 28 arranged between the universal bar and the base of the frame. As each type bar is thrown upwardly through the key-operated means its cam 22 depresses the universal bar, and through the movement of said bar the several groups of mechanisms are operated, said groups including the escapement means for controlling the letter space movement of the carriage; the ribbon vibrator and the ribbon feeding means.

On the main frame of the machine, in the rear of the type basket, is mounted a carriage supporting means or bed consisting of the carriage tracks 29 which extend transversely of the machine at the top of the main frame and are connected together by depending yokes 29^a. In the carriage tracks are formed opposed horizontal ways 30 in which are arranged two sets of bearing balls 31. The carriage is formed with longitudinally extending track flanges 32 which enter the ways 30 and ride on one set of balls 31 and bear against the other set of balls 31, one set of bearing balls supporting the carriage and the other set receiving the forward and rear thrust thereof. The carriage is provided with the upwardly extending end

brackets 33, said brackets being connected together at their lower ends by a suitable base plate, and the track flanges 32 are formed along the forward and rear edges of said base plate. A printing platen 34 is provided with a suitable supporting shaft which is journaled in the brackets 33 and carries at its ends the usual finger wheels 35 by which the platen may be rotated. Suitably secured to the rear part 5 of the main frame is a spring drum 36 in which is wound the usual motor spring for moving the carriage for letter space movement, said spring being connected to the carriage by any suitable form of band, as indicated at 37 in Fig. 1. Mounted on the base plate of the carriage, or formed integral therewith, is an escapement rack 38, and engaging said rack is a double-tooth escapement dog 39 which is mounted on a vertical pivot 40 rigidly secured in the middle yoke 29^a of the carriage supporting frame. The dog 39 is engaged by a vertically extending vibrating lever 41, the lower end of which is connected to the universal bar by a link 42, said link extending upwardly and forwardly to the universal bar as shown clearly in Fig. 1. The dog 39 is formed with a horizontal yoke 39^a in which is engaged the upper end of the lever 41; and the lever 41 is in two parts which are vertically slidable on each other, the lower part being connected to the link 42. The end cross bars or yokes 29^a of the carriage bed are provided with depending dove-tailed posts or slides 43 which fit corresponding slide-ways 44 formed on the sides of the frame 1. This permits the carriage bed and the carriage to be vertically moved for the case-shift positions of the platen.

Upon the movement of a type bar to the printing position its cam 22 will depress the universal bar, as previously described, and carry downward the forward end of the link 42. This movement will cause the link 42 to swing the lower end of the lever 41 rearwardly, thereby oscillating the escapement dog 39, thereby releasing one tooth of the dog from the carriage rack and bringing the other tooth into engagement therewith. When the type bar returns to its normal at-rest position the springs 28 return the universal bar to its upper position and, through the link 42 and lever 41, reverse the movement of the escapement dog, thereby permitting the carriage to move one letter space under the influence of the carriage moving spring. The yoke 39^a on the escapement dog permits the carriage to be shifted vertically without disengagement between the carriage dog and its vibrating lever 41. The sliding connection between the lower section of the lever 41 and the upper section thereof permits a free rearward movement of the lower end of the lever under the action of the link 42.

In the rear of the frame directly below the lower ends of the slide bars 43 is mounted a transverse rod 45. On this rod adjacent each post 43 are mounted two eccentrics 46 and 47 of different diameters, the eccentric 47 being of larger diameter than eccentric 46. Formed on the lower end of each slide post 43 is an inwardly extending foot 48 which is adapted to be engaged by the eccentrics, as shown clearly in Figs. 1 and 6. Connected to eccentric 47 is an operating arm 49, and connected to eccentric 46 is an operating arm 50, both of said arms extending to a suitable point above the eccentrics, as shown clearly in Figs. 1 and 6. Connected to the operating arms are forwardly extending links 51, said links being connected at their front ends to flexible key bars 52 which slide in tubes 53 and are provided at their upper forward ends with finger keys 54. The guide tubes 53 are rigidly secured in the rear ends of guide cups 13 rigidly secured to the cross-bar 13^a, and similar to the cups to which the guide tubes 12 are secured. In said cup and bearing on the tension bar 18 is a spring 55, said spring serving to return the operating keys and the connected eccentrics to their normal positions when the operating keys are released. The tension of the springs 55 will be adjusted whenever the tension bar 18 is moved through the adjusting rod 20. It is manifest that by moving the finger key connected to the eccentric 46 the connected operating arm 50 will be moved rearwardly and the eccentric so turned as to lift the carriage bed to its central case-shift position. It is also manifest that by operating the finger key connected to the shift eccentric 47 the carriage bed and the platen will be moved to its upper-case shift position. As shown in Fig. 4, two shift keys, with their connected eccentrics, are provided on each side of the keyboard.

To lock the platen in any one of its case-shift positions a wedge 56 is provided, said wedge being arranged to be projected in between the foot 48 of the slide posts and the eccentric engaged therewith. This wedge is connected to the rear end of a link 57, said link being connected to a locking key 58 by means of a flexible key bar precisely as the eccentric operating links 51 are connected to their finger keys. To release the carriage and permit it to return to its normal lower position it is only necessary to give a slight upward pull on the locking key. This removes the wedge from between the foot 48 and the engaged eccentric and permits the eccentric to be returned to its normal position.

Supported on the machine frame, on opposite sides of the type basket, are ribbon spools 59, said spools being mounted on vertical spool shafts 60, said spools being secured to said shafts by means of thumb nuts 61 screwed on the upper ends of said shafts. The lower ends of these shafts, below the type basket, are provided with ratchet wheels 62 through which the ribbon spools are rotated. Connected to the universal bar and extending forwardly therefrom at each of its ends, are links 63, the forward ends of which are connected to levers 64. On the free end of each of these levers is pivotally secured a cross head 65 on the ends of which are mounted pawls 66 and 66^a. Connected to the cross head 65 and extending to the outer side of the machine frame is a slidable rod 67 on the end of which is secured a finger piece or knob 68. By moving the rod 67 outwardly to the position shown in Fig. 4, the pawls 66^a are brought into engagement with the ratchet wheels 62. By forcing the said rod inwardly the pawls 66^a are released from the ratchet wheels and the pawls 66 brought into engagement therewith. It is obvious that by depressing the universal bar the link 63 is forced forwardly, thereby swinging the levers 64 on their pivots. The rocking motion imparted to the levers 64 will cause the pawls 66^a, when the parts are arranged as shown in Fig. 4, to rotate the ratchet wheels one tooth for each operation of the universal bar and thereby rotate the ribbon spools. It will be noted that, as indicated by arrows in Figs. 4 and 5, one spool will rotate to take up the ribbon while the other is rotating to let off. When it is desired to reverse the travel of the ribbon it is only necessary to slide the bar 67 to release one set of pawls from the ratchet wheels and to bring the other set into communication therewith. The pawls are provided with suitable springs to cause them to slip over and engage the teeth of the ratchet wheels; and the springs 28, in returning the universal bar to its normal position, will serve to also return the levers 64 and the pawls carried thereby to their normal positions.

Mounted on the central yoke or bracket 29^a of the carriage supporting bed is a lever 69, said lever being mounted upon a horizontal tubular pivot as shown clearly in Fig. 7. This lever is in the form of a bell-crank, having a shorter arm which extends downwardly and forwardly, and a longer arm 69^a which extends upwardly and forwardly. The said upwardly and forwardly extending arm 69^a of said lever is provided with a longitudinally extending slot; and embracing said arm at its upper end is a fork 70 which carries at its upper forward end the ribbon holder 71. Two pins extend through the arms of the fork 70 and through the slot in the arm 69^a; and a spring 72 connected to the fork and to the arm 69^a normally holds the ribbon holder in its lowermost position, as shown clearly in Fig. 1 of the drawings. The

lever 69 is provided with a rearwardly and downwardly extending slotted arm 73, in the slot of which is engaged a pin 74 carried by a vertically reciprocable bar 75. The lower end of this bar passes through a vertical guide 76 mounted on the upper end of a rod 77 whose lower end is rigidly fixed to the universal bar. It is manifest that by depressing the universal bar the rod 75 will be drawn downwardly and the ribbon holder thrown upwardly and rearwardly to the printing point through the arm 73 and the lever 69. The ribbon holder preferably extends forwardly and upwardly at an angle which leaves the printing point on the platen visible except when the ribbon is thrown to the printing point. When the carriage is moved upwardly for its different case positions the slot-and-pin connection between the rod 75 and the lever arm 73 will permit lever 69 to move upwardly with the carriage bed, the lever 69 slightly changing its angular relation to the carriage bed for the upper-case positions. However, as the downward movement of the rod 75 will swing the lever 69 on its pivot sufficiently to bring the ribbon to the printing point, without regard to the vertical shift of the carriage bed, this slight change in the position of the lever 69 for the upper-case positions will not be material.

In order to adapt the ribbon holder for bichrome ribbons or multiple-color ribbons, the fork of the ribbon holder is connected by a link 78 whose lower end is connected to a crank arm 79 of a horizontal rotatable rod 80 which extends through the tubular pivot of the lever 69. The outer end of the rod 80 is provided with an upwardly extending crank arm 81 to which is connected the rear end of a link 82. The forward end of said link 82 is connected to a bell-crank lever 83 which is mounted upon a horizontal pivot and adapted to be moved through a vertically arranged finger key 84. It is manifest from Fig. 1 of the drawings that by depressing the key 84 the crank arm 79 will be thrown upwardly and the connected link 78 will be moved outwardly on the lever 69, thereby projecting the ribbon holder upwardly and forwardly to bring a new portion of the ribbon into the path of the type bars at the printing point on the platen. By this means a two-color ribbon may be used. It is obvious that the finger key 84 may be provided with suitable stops or catches in order to secure the ribbon holder in its adjusted positions. When the finger key 84 is released the spring 72 will return the ribbon holder to its normal lower position, as shown in Fig. 1.

Mounted on the platen shaft is a line space lever 85 which carries a pawl 86 adapted to engage a ratchet wheel 87 secured to the end of the platen. The line space lever is adapt-

ed to vibrate between lugs 88 on one of the carriage end brackets 33 to limit the rotation of the platen through the line space lever. It is obvious that by swinging the line space lever upwardly and rearwardly through the limit of its movement, the platen will be rotated for line spacing.

The paper feed roll 89 is provided with eccentric bearings 90 mounted in the end frames of the carriage. Pivotedly connected to one of these eccentric bearings is an upwardly extending link 91 whose upper end is connected to the rear end of a paper-release lever 92. It is obvious that by depressing the forward end of the paper-release lever the paper feed roll will be rotated and withdrawn slightly from the platen to release the paper.

The carriage end frames or brackets are formed with rearwardly extending lugs 93 in which are pivoted the ends of a margin stop bar 94, said bar being provided on its forward side with teeth 95 adapted to be engaged by springs 96 carried by adjustable margin stops 97. Each stop is provided with a depending stop finger 98 shown clearly in Fig. 1. By forcing forwardly the free ends of the springs 96 said springs will be released from the notches of the stop bar and the stops may be then adjusted to any desired position on said bar. Upon a release of the springs 96 the stops will be locked in their adjusted positions. Secured to the rear of the carriage bed is an adjustable main stop 99, said stop being adjustably connected to a suitable bar on the carriage bed by means of a spring-pressed locking device 100. By drawing outwardly the said lock device 100 the main stop may be adjusted to any desired position on the carriage bed. To release the carriage stops from the main stop the stop bar is provided with an upwardly and rearwardly extending link 101 whose upper end is connected by a pin-and-slot connection to the rear end of a stop-releasing lever 102 which is pivoted upon the shaft of the platen. It is obvious that by depressing the forward end of the lever 102 the stop bar will be rotated and the stops 98 swung rearwardly free of the main stop 99.

Suitable alarm mechanism is operated through the carriage, the carriage rack bar 38 being provided with a long vertical lug 103 on its rear face which is adapted to engage the upper end of a lever 104 which carries at its lower end the bell striking device. The lug 103 is adjustable along the rack bar in order to operate the bell at any desired point.

A paper-finger supporting rod 105 is secured to the forward edges of the carriage brackets 33, and on said rod are mounted the usual paper fingers 106.

A space bar 107 is connected at each of

its ends by means of a flexible push rod 108 and a rigid link 109, to a universal bar operating lever 110 which is provided with a cam 111 similar to the cams on the type bars, 5 which cam is adapted to engage a roller on the universal bar. The space bar push rods are returned to their normal positions by means of a spring 19 precisely as described with respect to the type bar push rods.

10 These tension springs are arranged to engage the tension bar 18 and to be adjusted thereby, precisely as described with respect to the type bar actions.

From the foregoing it is manifest that I 15 provide a typewriting machine of very simple construction; of very few parts, and which is compact, light and of small dimensions. The flexible piano-wire operating rods 14 and the links 15 constitute what may 20 be properly termed a flexible push rod, the portion 14 thereof readily flexing and conforming to the curvature of the guide 12 as the key is depressed, and the movement of said flexible rod resulting in a rearward and 25 upward push or thrust on the link 15.

What I claim is:

1. A typewriting machine comprising a type bar pivoted at its rear end, a vertically movable finger key, a downwardly and rearwardly curved flexible wire push rod connected to said key, a tubular guide for said push rod, a rigid link connecting the rear end of said push rod to the type bar, and yielding tension means for returning the 35 push rod and key to their normal positions.

2. A typewriting machine comprising a type bar pivoted at its rear end, a vertically movable finger key, a downwardly and rearwardly curved flexible wire push rod connected to said key, a tubular guide for said push rod, a rigid link connecting the rear end of said push rod to the type bar, yielding tension means for returning the push rod and key to their normal positions, and 45 means for adjusting the tension means.

3. A typewriting machine comprising a series of type bars pivoted at their rear ends, a series of vertically movable finger keys, a downwardly and rearwardly curved flexible 50 wire push rod connected to each of said keys, a tubular guide for each of said push rods, a rigid link connecting the rear end of each of said push rods to a type bar, a yielding tension means for each push rod to return 55 said push rods and keys to their normal positions, and means for simultaneously adjusting all of said tension means.

4. A typewriting machine comprising a main frame, a carriage, a platen supported 60 in said carriage, means for moving the carriage transversely of the machine for letter spacing, an escapement mechanism, a universal bar, means connecting said universal bar to the escapement mechanism, pivoted type bars, a cam on the rear end of

each of said type bars adapted to engage and operate the universal bar, a finger key for each type bar, rigid links pivotally connected at their rear ends to the type bars forwardly of the type bar pivots, a flexible 70 push-rod connection between each key and the forward end of one of said links, means for guiding said flexible push-rods, and a tension means for each push rod adapted to return it to its normal position. 75

5. In a typewriting machine, the combination of a keyboard having printing and shift keys and a space bar, and push operated connections between said keys and space bar and the devices operable thereby embodying 80 a plurality of links each operatively connected at its rear end with its associated device, vertically reciprocable stems supporting the keys and space bar, means for guiding said stems, a flexible wire connection between each stem and the forward end of its associated link, and means for guiding said flexible wire connections. 85

6. In a typewriting machine, the combination of a frame, upwardly and rearwardly 90 movable type bars pivotally supported at their rear ends in said frame, links pivotally connected at their rear ends with said type bars in advance of the type bar pivots and provided with abutments at their forward 95 ends, a tension bar shiftably mounted in the frame provided with apertures through which said links extend, coiled springs surrounding the forward ends of said links between the abutments and tension bar, 100 means for adjusting the tension bar relatively to the abutments, a key for each type bar, vertically reciprocable stems slidably guided in the frame for supporting the keys, flexible wire connections between the 105 stems and the forward ends of the links, and means for guiding said flexible connections.

7. In a typewriting machine, the combination of a key-controlled device, a key, and an operating connection between the key and 110 said device embodying a vertically reciprocable stem supporting the key, a flexible wire connected at one end with the lower end of said stem, a downwardly and rearwardly extending guide for said wire, and a link 115 connected at its forward end with the rear end of said flexible wire and pivotally connected at its rear end with said device.

8. In a typewriting machine, the combination of a key-controlled device, a key, and an 120 operating connection between the key and said device embodying a vertically reciprocable stem supporting the key, a flexible wire connected at one end with the lower end of said stem, a downwardly and rearwardly 125 extending guide for said wire, a link connected at its forward end with said flexible wire and at its rear end with said device and provided with an abutment, an adjustable member having an aperture through 130

which said link extends, and a coiled spring interposed between said abutment and member and surrounding said link.

9. In a typewriting machine, the combination of key-controlled devices, a key for each device, a vertically reciprocable stem supporting each key, a guide for each stem, flexible wires connected at their upper ends with the stems, tubular guides for said wires extending downwardly and rearwardly from the lower ends of the stem guides, links pivotally connected at their rear ends with said devices and connected at their forward ends
- 10 with the rear ends of said wires and each carrying an abutment, springs coiled about 15 the links and engaging the abutments thereon at one end, a common tension bar for all of said springs having apertures through which the links extend, and means for slidably adjusting said bar toward and from the 20 abutments on said links to vary the compression of the coiled springs.

This specification signed this twelfth day of January, A. D. 1918.

PHILIPPE DE CLAMECY.
